Primary Examiner — Janice Hallmark*(74) Attorney, Agent, or Firm* — Hamilton, Brook, Smith & Reynolds, P.C.(57) **CLAIM**

An ornamental design for a desktop stand for mobile electronic devices, as shown and described.

DESCRIPTION

FIG. 1 is a front perspective view of a desktop stand for mobile electronic devices, showing my new design, in a closed position

FIG. 2 is a rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a bottom view thereof;

FIG. 9 is a perspective view of the desktop stand for mobile electronic devices, in an opened position;

FIG. 10 is a right side view thereof;

FIG. 11 is a left side view thereof;

FIG. 12 is a front view thereof;

FIG. 13 is a rear view thereof;

FIG. 14 is a top view thereof; and,

FIG. 15 is a bottom view thereof.

1 Claim, 15 Drawing Sheets(56)
